United States Patent Office

Des. 221,040

Patented June 29, 1971

221,040

TIRE

Arthur S. Ravenhall, Solihull, England, assignor to
Dunlop Holdings Limited, Birmingham, England

Filed Nov. 17, 1969, Ser. No. 20,149

Claims priority, application Great Britain July 1, 1969

Term of patent 14 years

Int. Cl. D12—14

U.S. Cl. D90—20

FIG. 1

FIG. 2

FIG. 3

FIG. 1 is a perspective view of the tire of my new design;

FIG. 2 is a fragmentary perspective view;

FIG. 3 is a fragmentary plan view.

It is to be understood that the tread pattern continues as shown throughout the circumference of the tire and the sidewall opposite to that shown in FIG. 1 is the same.

I claim:

The ornamental design for a tire, as shown and described.
